(22) Filed: **Dec. 23, 2002**

(57) **CLAIM**

(51) LOC (7) Cl. **14-03**

The ornamental design for a relay machine for wireless data communication, as shown.

(52) U.S. Cl. **D14/240**; D14/230

DESCRIPTION

(58) **Field of Search** D14/240-245,

FIG. 1 is a perspective view of a relay machine for wireless data communication showing my new design;

D14/230, 236, 237; 379/348, 344, 345;
755/106, 105; 343/795, 780, 700 R, 727

FIG. 2 is a front elevational view thereof;

(56) **References Cited**

FIG. 3 is a rear elevational view thereof;

U.S. PATENT DOCUMENTS

FIG. 4 is a left side elevational view thereof;
